Primary Examiner — George D. Kirschbaum*Assistant Examiner* — Lillian Windham(74) *Attorney, Agent, or Firm* — Ralph D Chabot(57) **CLAIM**

The ornamental design for a finish square, as shown and described.

DESCRIPTION

FIG. 1 is a top, front, left side perspective view;

FIG. 2 is a front elevation view;

FIG. 3 is a rear elevation view;

FIG. 4 is a left side elevation view, shown at a reduced scale;

FIG. 5 is a right side elevation view, shown at a reduced scale;

FIG. 6 is a top plan view;

FIG. 7 is a bottom plan view;

FIG. 8 is a top, rear, left side perspective view, shown in an alternate position; and,

FIG. 9 is a bottom, front, right side perspective view shown in the alternate position illustrated in FIG. 8.

The broken line portion of the figure drawings is included to show unclaimed subject matter only and forms no part of the claimed design.
